LAMP FILAMENT SORTING MACHINE

Erik C. Lindegaard, East Orange, N. J., assignor
to Westinghouse Lamp Company, a corpora-
tion of Pennsylvania

Application January 28, 1933, Serial No. 654,014

23 Claims. (Cl. 209—82)

This invention relates to the manufacture of incandescent electric lamps and relates more particularly to a machine for sorting helically coiled filaments according to overall lengths.

5 Incandescent lamps as constructed in accordance with modern practice include a helically coiled filament usually comprised of fine tungsten wire. These filaments contain definite amounts of wire and constitute a resistance element which, 10 upon the passage of electrical energy therethrough, become heated to incandescence and constitute a light source.

Coiled filaments may be made either by winding a filamentary wire upon a mandrel and cutting the mandrel wound wire into sections of predetermined lengths or they may be wound by means of what is termed a mandrelless coil-winding machine wherein the filamentary wire is coiled to the desired pitch and diameter in the absence 20 of a mandrel. As the filamentary wire is coiled and coils issue from the mandrelless machine they are cut into sections of predetermined lengths.

The production of incandescent electric lamps 25 is attended by certain definite requirements insofar as the dimensions and proportions of the component parts of the lamps are concerned so that the finished product will be of a quality to meet the manufacturer's standard.

30 Although mechanism is provided for cutting an indefinite length of helically coiled filament into sections of uniform length, insofar as the actual amount of wire is concerned in a given coiled section, the overall lengths of the coiled 35 sections may vary slightly. It becomes necessary, therefore, to sort the coils and to select or remove coiled sections which do not fall within the limits of certain predetermined overall lengths.

The sorting of the coils to collect groups of 40 coils of similar lengths is of particular importance in connection with the use of an automatic mounting machine. The high-speed production of lamps has made it desirable to provide machines for automatically mounting coiled sections 45 and mechanism is therefore provided for positioning the coiled sections and clamping or welding the ends to lead wires of a lamp stem. The automatic mounting of lamp filaments makes it necessary to provide coiled sections of definite 50 and uniform overall lengths so that when positioned to be received by a mechanism for performing the automatic mounting operation, the means, such as the jaws which grip the ends of the filamentary section, may be given a fixed position 55 and the filaments or coiled sections may be fed

thereto without failure of the jaws to grip the ends of the filament by reason of a difference in the overall filament lengths.

It is an object of the present invention, therefore, to provide means for automatically selecting coiled sections of uniform lengths.

Another object of the invention is to provide a machine for selecting coiled sections of different lengths and for collecting sections of similar lengths in groups.

Other objects and advantages of the invention will be more clearly understood by reference to the following description together with the accompanying drawings, in which:

Figure 1 is a plan view of a coiled sorting machine constructed in accordance with the present invention;

Figure 2 is a longitudinal sectional view taken on line II—II in Fig. 1;

Figure 3 is a view taken on line III—III in 20 Fig. 2;

Figure 4 is a view taken on line IV—IV in Fig. 2;

Figure 5 is a view taken on line V—V in Fig. 2;

Figure 6 is a view taken on line VI—VI in 25 Fig. 2;

Figure 7 is a fragmentary perspective view showing a jaw actuating plunger;

Figure 8 is a fragmentary perspective view showing an adjustment block for longitudinal adjustment of a jaw;

Figure 9 is a fragmentary perspective view partly in section showing a gauge rod for use in gauging the length of a coiled section;

Figure 10 is a fragmentary detailed view showing a ratchet driving rod; and

Figure 11 is an enlarged plan view partly in section showing gauge members and gripper jaws in various positions during the gauging operation.

Although the present invention may be employed to sort elongated articles capable of being gripped at their ends, the selected embodiment of the invention is especially constructed to sort sections 9 of coiled filamentary wire. Sections of helically wound filament which may be termed coils are cut from windings of indefinite length and, as above pointed out, slight variations occur in the overall lengths of the coils.

The present machine, therefore, operates to handle the extremely fine filaments and sorts 50 them into groups, each group containing coils of a given length.

The main operating elements of the machine may include head 10, a coil-removing head 11 and a coil-receiving element 12. The sorting 55

head 10 is rotated and the coil removing head 11 is reciprocated to and from operative position with the sorting head. Mechanism for actuating the sorting and removing means may comprise 5 a motor 13 having suitable reduction gear box 14 provided with a driving gear wheel 15.

The gear wheel 15 is disposed in mesh with a gear wheel 16 loosely mounted on a horizontal shaft 17 journaled in bearings 18 and 19. The 10 bearing 18 may be integral with a base plate 21 and the bearing 19 may be integral with a bearing plate 22 suitably positioned with respect to the motor and other operating mechanisms. The gear wheel 16 is provided with pawls 16' and 16'' 15 which engage a ratchet wheel 17' secured to the shaft 17. This construction makes it possible for an operator to move the various operating parts of the machine by turning a fly wheel 20 which is secured to the shaft 17 and which serves 20 to actuate the coil sorting mechanism in a manner to be later described. Inasmuch as the machine may be operated by turning the fly wheel 20 by hand it is possible to readily make the necessary adjustments of the coil-sorting elements by trial.

The horizontal shaft 17 is provided with a bevelled gear 23 in mesh with a bevelled gear 24 and one end of a shaft 25. The shaft 25 may be journaled in a bearing 26 on the bearing plate 30 22 and a bearing 27 on a suitable supporting bracket 28. The opposite end of the shaft 25 is provided with a disc 29 having an eccentrically disposed wrist pin 31 to which one end of a connecting rod 32 is pivotally attached. The other 35 end of the connecting rod 32 is pivotally attached to an arm 33 (see Fig. 10) pivoted on a shaft 34 and carrying a dog 35 for engagement with teeth 36 of a ratchet wheel 37.

The arm 33 is loosely mounted on the shaft 40 34 and the ratchet wheel is pinned or otherwise secured to the shaft. Thus an oscillatory movement of the arm 33, by reason of the motion translated from the shaft 25, will cause an intermittent rotary motion of the shaft 34 about its 45 longitudinal axis. The shaft 34 is disposed in a stationary guide bushing 38 rigidly secured in a bracket 39. At one end of the shaft 34 is secured a cylindrical conveyor 41 movable upon a rotation of the shaft 34. Intermediate the conveyor and the bracket 39 is a stationary cam member 42. This cam member is mounted on and secured to the bushing 38 by a suitable set screw and is held in position by a lock collar 43.

A dowel or steady pin 44 extends from the bracket 39 and into an aperture in the body of the stationary cam member 42 to hold the same in a definite position. The cylindrical conveyor 41 is provided with equally spaced longitudinal slots 45 to receive coiled sections from a source of 60 supply 46.

Means for depositing the coiled sections in the slots 45 may comprise a pair of gripper jaws 47 operable to pick up a coil from the supply 46 and drop it through a chute 48 onto a guide surface 49 and thence into a positioned slot. Jaws, operable to pick up coils for deposit, are shown in co-pending application Serial No. 487,238 filed October 8, 1930, which application is assigned to the assignee of the present invention.

In the absence of coil-depositing mechanism, such as the gripper jaws 47, coils may be deposited in the chute 48 by hand. The slots 45 which receive the coils may be of any suitable number spaced around the periphery of the conveyor and each slot is provided with an ex-

tending lip 51 to maintain the coils on the conveyor until each slot has reached the lowest position of its movement whereupon any coil remaining in the slot will be deposited in a receptacle 52. As will be later described, the coils which are carried around with the conveyor and deposited in the receptacle 52 are coils which are of a length too short to be within the range of selection.

For the purpose of positioning coiled sections in definite relation to their respective slots, each slot is provided with a push rod or gauge 53. Each push rod is provided with a spring member 54 (see Fig. 9) in the form of a member having two arms 55 and 57 connected by a coiled section. Each of the arms 55 and 57 is tensionally urged away from the other and the arm 55 engages a head 56 on the push rod 53 and arm 57 engages a bushing 58 in which the push rod is movable.

The spring member 54 for each push rod is clamped in a skirt 59 extending from a hub 61 on the conveyor 41. When the conveyor is moved the heads 56 of the push rods engage cam surface 62 of the cam member 42 and tend to move 25 a coiled section along its slot. The movement of each push rod 53 is regulated so that upon its complete movement the distance between its end and the edge of the slot 45 will be a fixed distance.

Thus, if a coiled section is of sufficient length to project beyond the edge of the conveyor (see Fig. 11) a pair of jaws 63 will be operated, by means presently to be described, to remove the coil and drop it into one of a number of receptacles 64 positioned at the bottom of the coil-receiving element 12. Five receptacles 64 are employed in the present construction and each receptacle is positioned beneath guide plates or partitions 64' which direct coils released from the jaws into separate receptacles. The receptacles are removable so that collected quantities of coiled sections of uniform lengths may be removed.

As above mentioned, if a coiled section is dropped into one of the slots 45 and it projects more than a predetermined distance, it is first adjusted by a centering plunger 65 and then moved inwardly by an adjustor plunger 66. After the adjustor plunger 66 has moved the coiled section inwardly leaving it to project a predetermined distance, one of the gauges or push rods 53 is moved to engage the inner end of the coiled section. If the coiled section is of a given predetermined length, the push rod will contact with the inner end of the coil without moving forward.

If, however, the coiled section is of a length greater than the distance between the advanced face of the adjustor plunger 66 and the end advanced, one of the push rods 53 will move the coiled section outwardly and the distance the coil extends from the edge of the conveyor will, obviously, be greater than the distance between the advanced face of the adjustor plunger 66 and the edge of the conveyor. If the coiled section is too short it will remain in its slot and be projected beyond the edge of the conveyor and will thus be carried around and eventually discharge in the receptacle 52.

It will be appreciated that the coils or coiled sections, as they are received from the cutting mechanism, are cut within extremely narrow limits for length and the only variation in the lengths of the severed coils occurs by reason of slight variations in the pitch or slight irregularities.

ties in winding so that although the drawings, particularly Fig. 11 which is an enlarged view, show seemingly great variation in lengths, such variation is very small and the selection of coils is carried out to an extremely fine degree.

The mechanism for gripping and removing the coiled sections constitutes the coil-removing head 11 and is equipped with five of the heretofore mentioned coil-gripping jaws 63 which may, as a whole, be considered as coil-removing members 67. These members have a scissor-like construction and comprise lever members 68 and 69. The lever member 68 is provided with a short arm 71 and a long arm 72 and the lever member 69 is provided with a short arm 73 and a long arm 74. These arms are pivotally mounted on a pin 75 and are free to rock as a unit about the pin 75, which is mounted on a slide block 76 between guide plates 76'.

20 A tension member 78 mounted on the pin 75 is provided with oppositely actuating arms to normally hold the jaws 63 closed. For the purpose of opening the jaws each coil-removing member is provided with a jaw-opening plunger 79 mounted on a movable cross-head 81 and held by a set screw 82. The plunger 79 is provided with an eccentrically disposed contact end 83 and a knurled finger piece 84 so that by adjusting the set screw 82 the contact end 83 may be adjusted about the longitudinal axis of the plunger. The purpose of this adjustment is to cause a slight movement in the position of the coil-removing member as a unit after the jaws are opened.

It is evident that the plunger may also be adjusted endwise to vary the position of the contact end 83 so that the jaws may be opened or closed in predetermined time relation.

A further adjustment of coil-removing members 67 is accomplished by means of an adjustment screw 84' (see Figs. 2 and 8) held in a slot 85' in plate 96. The screw 84' threadedly engages the threads 86' in a slide block 76. This adjustment means makes it possible to move the coil-removing members 67 so as to vary the length of the portions gripped by the jaws 63.

By reason of the construction and adjustability of the plunger 79 they may, by trial, be adjusted to guide the jaws 63 into their proper positions to grip a coil positioned in a slot. It will be appreciated that, inasmuch as a slight variation occurs in the space relation of the coiled sections, each of the members 67 must be slightly adjusted, which adjustment is readily accomplished by the means afforded. Once the adjustment is made, the machine may operate continuously.

For the purpose of actuating the coil-removing member 67, as well as the plunger 79, mechanism, as more clearly shown in Fig. 2, is provided. This mechanism may comprise a slide carrier 85 movable on a table 86 integral with the base plate 21. The slide carrier has a vertical extension 87 at one end on which the coil removing members 67 are mounted.

65 A stop plate 88 having adjustable stop screws 89 is provided to limit and adjust the forward movement of the slide carrier 85. Slidably mounted on the slide carrier 85 is the cross-head 81 having a base portion 91 provided with a pin 92 to which one end of a crank arm 93 is pivotally attached. The other end of the crank arm is pivotally attached to a wrist pin 94 eccentrically positioned on a fly-wheel 20 secured to shaft 17. The cross-head 81 is movable relative to the carrier 85, such movement being limited be-

tween stop plates 95 at one end of the carrier and a plate 96 at the other end thereof.

When the crank-arm 93 is operated to move the cross-head toward the coil-removing members 67, the plunger 79 engaging said members, are operated to open the jaws thereof and, by reason of the contact between the push rod 81' of the cross-head and the stop plate 96, the jaws are moved into position to grip ends of coiled sections extending from the conveyor. An opposite movement of the crank arm 93 moves the cross-head 81 thus removing the plunger 79 from operative relation to the members 67, permitting the jaws to grip coiled sections.

The cross-head continues in its reverse movement until a stop member 97 thereof engages the stop plate 95 whereupon the cross-head causes the carrier 85 to move away from the conveyor into position to deposit the coiled sections over the several receptacles. A continued operation of the crank-arm results in a return movement of the cross head bringing the plunger 79 into engagement with the members 67, causing the jaws to open and the coils to be deposited in their respective receptacles. A continued movement of the crank arm 93 repeats the operation of opening the jaws at which time other coiled sections have moved into position to be gripped thereby. As the cross-head 81 is actuated the centering plunger 65 and the adjuster plunger 66 are operated.

Although the present machine is operable to select filaments having predetermined lengths, the present arrangement of the operating elements serves to select filaments having lengths within given limits.

The lamp filaments as they are received from the coil winding machine, vary in length from 38 to 42 millimeters. The present machine is provided with five sets of coil or filament removing members, the first set serving to remove filaments of over 42 millimeters in length; the second set removing filaments between 42 and 41 millimeters; the third set removing filaments between 41 and 40 millimeters; the fourth set removing filaments between 40 and 39 millimeters and the fifth set serving to remove filaments between 39 and 38 millimeters.

The above arrangement of the jaws, as well as the schedule for the selection of sizes, is given merely as an example of a practical embodiment of the invention. It is, of course, to be understood that more or less jaws may be employed and that the selection may be either narrowed or broadened depending upon the degree of difference required in the selection of filaments. If desirable, the machine may be operated to select filaments of only one size or to select filaments of several predetermined sizes or lengths.

It has been found, in the use of filaments in connection with a mounting machine, that filaments separated in accordance with the schedule above given, answer manufacturing requirements in the automatic mounting of lamp filaments.

In the operation of the machine, filaments are fed either automatically or by hand through the chute 48 for deposit in the slots 45 disposed longitudinally on the outer surface of the conveyor which is shown in the form of a drum. The drum rotates in the direction indicated by the arrow (see Fig. 3) and if the filament deposited in a slot is less than 38 millimeters, it will be carried around with the conveyor and, as above mentioned, will be deposited in the receptacle 52. However, if the filament is of greater length than 75

38 millimeters, and it lies in a slot with one end projecting, the adjuster members 65 and 66 will move it until an end of the filament extends from the edge of the slot a predetermined distance.

5 This distance removes the end of the filament from a path of travel which would bring it in position to be gripped by one of the pairs of jaws 63. As the conveyor rotates, however, the plungers 53 engaging with the cam 42 are moved and the filament is caused to move endwise and project from the edge of the conveyor a sufficient distance to bring the end of the filament into position to be gripped by a pair of jaws.

10 As will be noted, the plungers 53 have different degrees of movement by reason of the formation of the cam surface 62. The coil-removing members 67 (see Fig. 11) are indicated by reference letters A, B, C, D, and E each member being disposed adjacent to a plunger 53 which engages different portions of the cam surface 62. Thus filaments disposed in the slots will be moved forward different distances.

15 If a filament is over 42 millimeters it will be removed by coil-removing member A since the distance between the end of the plunger opposite the member A and the jaws 63 is 42 millimeters or more, thus permitting the jaws 63 to receive the end of a filament of that length. If a filament is between 41 and 42 millimeters the plunger 20 53 opposite to member B will move it forward one millimeter and it will be gripped by the jaws 63 on the member B. The degree of movement of the plungers 53 has been set at one millimeter and it will be evident that the jaws opposite each plunger serve to secure the ends of all filaments within one millimeter difference. If the filament is between 40 and 41 millimeters it will not be secured by the jaws on member B but when moved opposite to member C the plunger 25 53 will move it so that an end is received. The same operation follows for filaments as they reach coil-removing members D and E.

30 The movement of the conveyor drum is intermittent by reason of the pawl 35 and ratchet 36 and after each movement of the conveyor it has a stationary period during which time the coil-removing members are advanced and retracted. This operation is accomplished by means of the crank arm 93. As the members 67 are moved 35 forward the actuating plungers 83 engage and separate the arms 71 and 73 of each member thus opening the jaws 63 to receive the end of a filament.

35 It has been found that although the slots 45 are disposed in equal space relation on the drum, the filaments vary in their respective space relation by reason of the tangential relation of the slots to the periphery of the drum. One filament will be at the bottom of a slot and the next at one side or off center with respect to the bottom and so on. This condition makes it difficult to determine the space relation required for the jaws 63.

40 The present construction, therefore, as above described, provides the eccentric plungers 83 which serve not only to open the jaws but to move the members 67 about their pivot so that the several pairs of jaws may each be adjusted by reason of the adjustability of the plungers 83. 45 As each plunger moves to open the jaws it bears against an arm of the member adjusting the member bodily.

45 The position of the jaws 63 is determined by trial and when once adjusted the machine operates without further attention insofar as the

space relation of the filaments in their respective slots is concerned. When the members 67 have been moved forward the jaws 63 are in position to grip the end of any filament extending such a distance that its path of movement will bring it between a pair of jaws.

5 The plungers 83 then withdraw from between the arms of the members 67 and the jaws close under the action of their springs 18.

10 The members 67 all retract after an actuation of their jaws and filaments secured between jaws are moved over the respective receptacles. As the plungers 83 again come forward the jaws are opened and the filaments drop into the different receptacles and are thus assorted for length.

15 Although a preferred embodiment of the invention is shown and described herein, it is to be understood that modifications may be made therein without departing from the spirit and scope of the invention as set forth in the appended 20 claims.

What is claimed is:

1. A machine for sorting filaments according to length comprising a drum, said drum having longitudinal slots to receive filaments of different 25 lengths, means movable along said slots for moving filaments endwise a predetermined distance in said slots to project ends thereof from said support, means for moving said support to cause said filament ends to travel through a given path, 30 a plurality of pairs of jaws, means for supporting said pairs of jaws in given positions with respect to the path of movement of said ends, means for actuating said pairs of jaws to grip an end moving into range thereof, means for opening said 35 jaws to release gripped filaments and means for collecting filaments gripped by the respective jaws into separate groups.

2. A machine for separating elongated articles of different lengths into groups comprising a support for articles, push rods for engaging ends of 40 said articles to move them to predetermined positions on said support, a carriage, means on said carriage for gripping the ends of said articles and means for moving said support to position 45 said articles for removal, means for moving said carriage to position said first mentioned means to grip said articles and means for causing said gripped articles to be released.

3. A machine for separating elongated articles 50 of different lengths into groups comprising a support for articles, individually operable means for moving said articles to predetermined positions on said support, a carriage, article gripping means mounted on said carriage, means for moving said carriage to position said gripping means to grip articles, means for moving said gripping means to remove said articles from said support and means for actuating said gripping means to release said articles.

4. A lamp filament sorting machine comprising a filament support, individually operable means for moving said filament to project an end thereof from said support, a carriage, filament gripping means mounted on said carriage, means for moving said filament support to position a projecting filament to be secured by said gripping means, means for moving said carriage to position said gripping means to secure the end of said filament, means for actuating said gripping 70 means to secure said end and means for moving said carriage to remove said filament from said filament support.

5. A lamp filament sorting machine comprising a support for filaments, a push rod for engaging

- an end of each filament, means for individually actuating said push rods for moving said filaments to project ends thereof from said support, a carrier, filament gripping means mounted on 5 said carrier, means for moving said support to position a projecting filament end to be secured by said gripping means, means for moving said carrier to position said filament gripping means adjacent the ends of positioned filaments, means 10 for actuating said gripping means to secure the ends of said filaments, means for actuating said carrier to remove said filaments from said support and means for releasing said filaments from said gripping means.
- 15 6. A filament sorting machine comprising a rotatable carrier, said carrier having slots to receive filaments, plungers movable in said slots for adjusting filaments in said slots to project the ends of the filaments, a carriage, a plurality 20 of pairs of gripper jaws on said carriage, means for moving said carrier to position filament ends adjacent to said gripper jaws, means for moving said carrier to position filament ends between said jaws and means for actuating said jaws to grip the ends of said filaments.
- 25 7. A filament sorting machine comprising a rotatable carrier, said carrier having slots to receive filaments, individual filament adjustor members movable in said slots, means for moving said carrier, means for actuating said members to position filaments in predetermined positions in said slots, a reciprocal carriage, gripping members for securing the ends of positioned filaments, means for actuating said carriage to position said members to grip said filaments and means for actuating said carriage to remove filaments from said slots.
- 30 8. A filament sorting machine comprising a conveyor having slots to receive filaments, individual filament adjustor members for moving filaments to predetermined positions in said slots, a carriage movable to and from said conveyor, a plurality of pairs of jaws mounted on said carriage for gripping the ends of said filaments, means for moving said carrier to position filaments adjacent to said pairs of jaws, means for moving said carriage toward said conveyor, means for actuating said jaws to grip said filaments and means for moving said carriage away from said conveyor to remove filaments.
- 35 50 9. A filament sorting machine comprising a conveyor having slots to receive filaments, individual filament adjustor members for moving said filaments to predetermined positions in said slots, a movable carriage, a plurality of pairs of jaws for gripping the ends of said filaments mounted on said carriage, means for moving said conveyor to position filaments adjacent said pairs of jaws, means for moving said carrier to position said 40 jaws to grip said filaments, means operable upon a movement of said carriage to cause said jaws to grip said filaments for removal from said conveyor and means for opening said jaws to release said filaments.
- 45 60 65 10. A machine for separating filaments of similar lengths into groups comprising a support for receiving a plurality of filaments of different lengths, individually operable means for moving said filaments endwise a predetermined distance to project the ends thereof from said support, a carriage, jaws for gripping a predetermined portion of the end of a filament mounted on said carriage, means for progressively moving said filaments into position to be gripped, means for mov-

ing said carriage to position said jaws to grip the ends of filaments and means operating in timed relation with the movement of said carriage to operate said jaws.

11. A machine for separating filaments of similar lengths into groups comprising a support for receiving a plurality of filaments of different lengths, push-rods for moving said filaments endwise a predetermined distance to project the ends thereof from said support, a reciprocal carriage, 10 jaws for gripping predetermined portions of the ends of filaments mounted on said carriage, means for progressively moving said filaments into position to be gripped, means for actuating said jaws to grip said ends and means for depositing gripped 15 filaments in a common group.

12. A machine for collecting filaments of similar lengths into groups comprising a support for a plurality of filaments of different lengths, a member movable along the longitudinal axis of each 20 filament for moving said filaments endwise a predetermined distance to project the ends thereof from said support, a carriage, a plurality of gripper members mounted on said carriage and positioned to grip predetermined amounts of extended filament ends when said carriage is moved, means for moving said support to progressively position the filament ends to be gripped, means for moving said carriage to position said members to grip said ends and means for actuating said 25 members to grip filament ends projecting from said support.

13. A machine for collecting filaments of similar lengths into groups comprising a support for a plurality of filaments of different lengths, a plurality 30 of members for engaging the ends of the filaments, means for individually actuating said members to move said filaments endwise a predetermined distance to project the ends thereof from said support, a carriage, a plurality of gripper members mounted on said carriage and positioned to grip predetermined amounts of extended filament ends when said carriage is moved, means for moving said support to progressively 35 position the filament ends to be gripped, means for moving said carriage to position said members to grip said ends, means for actuating said members to grip filament ends and means for moving said carriage to remove filaments from said support.

14. A machine for sorting filaments according to length comprising a drum, said drum having longitudinal slots to receive filaments of different lengths, means movable along said slots for moving filaments endwise a predetermined distance 40 in said slots to project ends thereof from said support, means for moving said support to cause said filament ends to travel through a given path, a carriage, a plurality of pairs of jaws, a carriage for moving said pairs of jaws in given positions 45 with respect to the path of movement of said ends, and means for actuating said pairs of jaws to grip a filament end moving into range thereof.

15. A machine for sorting filaments according to length comprising a drum, said drum having 50 longitudinal slots to receive filaments of different lengths, means movable along said slots for moving filaments endwise a predetermined distance in said slots to project ends thereof from said support, means for moving said support to cause 55 said filament ends to travel through a given path, a plurality of pairs of jaws, means for supporting said pairs of jaws in given positions with respect to the path of movement of said ends, means for actuating said pairs of jaws to grip an end mov-

ing into range thereof, means for opening said jaws to release gripped filaments and means for collecting filaments gripped by the respective jaws into separate groups.

5. 16. A machine for separating filaments according to length comprising a cylindrical conveyor, longitudinal filament receiving slots on said conveyor, means movable along said slots for moving filaments endwise in said slots, a carriage, a plurality of pairs of coil-gripping jaws mounted on said carriage, means for moving said carriage to dispose said members in position to grip said filaments, means operable upon a movement of said carriage in one direction for opening said jaws and means operable upon a movement of said carriage in another direction for closing said jaws.

10. 17. A machine for separating filaments according to length comprising a cylindrical conveyor, longitudinal filament receiving slots on said conveyor, means movable along said slots for moving filaments endwise in said slots, a carriage, a plurality of pairs of coil-gripping jaws mounted on said carriage, means for operating said jaws to grip filaments, means operable upon a movement 15 of said carriage in one direction to open said jaws to release said filaments.

15. 18. A machine for separating filaments according to length comprising a cylindrical conveyor, longitudinal filament receiving slots on said conveyor, means movable along said slots for moving filaments endwise in said slots, a carriage, a plurality of pairs of coil-gripping jaws for securing the ends of said filaments, means for closing said jaws to secure filaments, means for moving said carriage to remove said filaments from said conveyor and means operable during movement of said carriage for opening said jaws.

20. 19. A machine for sorting filaments according to lengths comprising a support for filaments, means for moving said filaments endwise to project ends thereof from said support, a carriage, a plurality of pairs of gripper members mounted on said carriage, a pair of gripper jaws on each of said members, means for closing said jaws, means movable relative to said carriage for opening said jaws, said means operating upon a movement of said carriage to close said jaws and means for moving said carriage to move said filaments endwise for removal from said support.

25. 20. A machine for separating elongated articles of different lengths into groups comprising a support for holding said articles in spaced relation, a plurality of receptacles arranged to receive said articles, means for moving said articles endwise on said support to project ends thereof over one side of said support, means for moving said support to successively position said extended articles adjacent to said receptacles, a plurality of pairs of gripping jaws, means for moving each

pair of jaws to grip an end of an article extended a predetermined distance from said support, means for moving said jaws to remove gripped articles from said support and means for actuating said jaws to release said articles for the deposit of articles of one length into one receptacle and articles of a different length into another receptacle.

30. 21. A machine for separating elongated articles into different groups comprising a support for holding articles in spaced relation, a carriage, a plurality of pairs of gripping jaws mounted on said carriage, a plurality of receptacles disposed in spaced relation between said support and said carriage, means for moving said articles to extend 15 their ends a predetermined distance from said support over different receptacles depending on the lengths of the articles, means for moving said carriage to position said jaws to grip the extending ends of said articles.

35. 22. A machine for separating elongated articles into different groups comprising a support for articles, means on said support for holding articles in spaced relation, a pusher rod for moving each article, means for intermittently moving 25 said support, means for moving said pusher rods a given distance during each movement of said support, a receptacle under each supported article, said pusher rods serving to engage said articles and move the same to extend the ends of 30 articles of different lengths over different receptacles and means operating with each intermittent movement of said support to deposit in a receptacle articles having their ends extended a predetermined distance.

40. 23. A machine for separating elongated articles into different groups comprising a support for articles, means on said support for holding articles in spaced relation, a pusher rod for each article, means for each pusher means for intermittently moving said support, means for moving said pusher rods a given distance during each movement of said support, a receptacle to receive articles under each supported article, said pusher rods serving to engage said articles and move the 45 same to extend the ends thereof from one side of said support, articles of different lengths having their ends extended while over different receptacles, gripper jaws movable over each receptacle to grip extended ends of articles, means for moving said jaws to grip said ends with each movement of said support, means for actuating said jaws to grip articles having their ends extended a predetermined distance, means for removing said jaws to move gripped articles from said support 50 and means for actuating said jaws to release articles for deposit in said receptacles.
